(No Model.)

W. D. ROBINSON.

POTATO DIGGER.

No. 245,868.

Patented Aug. 16, 1881.

UNITED STATES PATENT OFFICE.

WILLIAM D. ROBINSON, OF AVOCAS, NEW YORK.

POTATO-DIGGER.

SPECIFICATION forming part of Letters Patent No. 245,868, dated August 16, 1881.

Application filed May 19, 1881. (No model.)

To all whom it may concern:

Be it known that I, WILLIAM D. ROBINSON, of Avoca, Steuben county, New York, have invented a certain new and useful Improvement in Potato-Diggers; and I do hereby declare that the following is a full, clear, and exact description of the same, reference being had to the accompanying drawings, in which—

Figure 1 is a side elevation of a potato-digger, showing my improvement. Fig. 2 is a plan of the same. Fig. 3 is a rear elevation. Fig. 4 is a view of one of the chains which drag in the rear of the plow. Figs. 5 and 6 are modifications.

My improvement relates to potato-diggers mounted on wheels connected with springs which support the beam and handles; and the invention consists in the construction and arrangement of parts hereinafter more fully described.

In the drawings, A is the beam, which resembles a plow-beam, except that it is of such length that it extends forward and connects directly with the neck-yoke of the horses, by which means the implement is properly guided and a fulcrum or resistance is obtained for operating and controlling the handles.

B B are the handles, which also resemble plow-handles, and C is a standard projecting down from the under side of the beam, and having upon its lower end a point, a, which may be either single or double winged, which passes through the rows and throws out the potatoes.

D D are two cross-bars, bolted securely on the under side of the beams at suitable distance apart.

E E are half-elliptic springs at opposite ends of the cross-bars, and connected with clips at the ends of the cross-bars, so that the springs have a free movement. The springs curve downward, as shown.

F is a curved axle for striding the rows, being bolted at its outer ends to short journals b b, upon which are supporting-wheels G G, which run upon the ground between the rows. The center of the springs rests upon the ends of the curved axle by means of intermediate blocks, c c, and are clipped or bolted thereto.

By the means above described an elastic connection is interposed between the supporting-wheels and the beam, which, while it supports the beam and plow, is made to yield both

upward and downward by suitable pressure on the handles, so that the plow may be made to follow at a uniform depth in the row, whatever may be the undulations or irregularities of the ground, and the work is accomplished with great ease to the operator. The end of the beam resting in the ring of the neck-yoke forms the fulcrum or resistance necessary in operating the handles, as before described. The location of the springs on opposite sides and at some distance apart gives stiffness and form to the upper parts.

Instead of the elliptic springs shown, torsion, spiral, rubber, or other suitable springs may be employed.

By the use of the springs and wheels it is not necessary to tilt or turn the plow sidewise, as in other devices where the plow is used.

By the use of the wheels the operator, pressing sidewise, can make the plow follow the undulations of the rows without difficulty.

P is a lever pivoted to the beam, to the lower end of which the center of the curved axle is attached by a chain, i. This lever extends above the plow-handles within convenient reach of the operator. A ratchet-bar or other device, r, may be used in connection with the lever to hold it at any position. By this means the plow may be gaged to cut deeper, or it may be raised to run clear of the ground.

L L are a series of chains attached to the rear of the plow, and serving to throw out the potatoes and clear the vines of dirt. Four of these chains are preferably used, and each chain consists of links formed in the shape of the figure 8, one half of each link being vertical and the other half horizontal. Figs. 5 and 6 show one form of torsion-springs.

Having thus described my invention, I claim—

In a potato-digger, the combination of the beam A, cross-bars D D, springs E E, curved axle F, supporting-wheels G G, and the lever P, connected with the axle by chain i, as shown and described, and for the purpose specified.

In witness whereof I have hereunto signed my name in the presence of two subscribing witnesses.

WILLIAM D. ROBINSON.
